Primary Examiner — Mitchell I. Siegel(74) *Attorney, Agent, or Firm* — Oliff PLC(57) **CLAIM**

The ornamental design for a golf club head, as shown and described.

DESCRIPTION

FIG. 1 is a front, toe-side, top perspective view of a golf club head, showing the new design;

FIG. 2 is a front elevational view thereof;

FIG. 3 is a rear elevational view thereof;

FIG. 4 is a toe-side elevational view thereof;

FIG. 5 is a heel-side elevational view thereof;

FIG. 6 is a top plan view thereof;

FIG. 7 is a bottom plan view thereof; and,

FIG. 8 is a top, toe-side, rear elevational view thereof.

The broken lines depict parts of the golf club head that form no part of the claimed design.
